ROLLING MILL

Carl Schmidt, Baeri, Germany

Application September 8, 1932, Serial No. 632,212
In Germany September 18, 1931

6 Claims. (Cl. 89—16)

My invention relates to rolling mills, and more particularly to mills for rolling revolution bodies from disk-shaped blanks or blocks, in which a platen for supporting the blank cooperates with a pair of opposed blank-working rolls, and the rolls are traversed and retraversed over the platen.

In mills of the aforesaid type as designed heretofore, the platen and the rolls are driven.

It is an object of my invention to improve the mill.

To this end, I drive only the rolls and not the platen.

I have found that in a mill according to my invention, with driven rolls and an idle platen, much higher rolling pressures can be exerted than in the old mills in which both the platen and the rolls are driven, without sticking of the parts, which inevitably occurs in the old mills if a certain, and not very high, limit of the pressure is overstepped.

In the accompanying drawings, a mill embodying my invention is illustrated by way of example, with some specimens of its work.

In the drawings

Fig. 1 is an elevation, and

Fig. 2 is a plan view, of the complete mill,

Figs. 3 and 4 are part elevations illustrating two stages of rolling a flat disk from a blank,

Fig. 5 is a section of a disk having a flat face on one side, and a tapered face on the other,

Figs. 6 and 7 are sections of cups, and

Fig. 8 is a section of a hub-and-disk wheel, all to be rolled on my improved mill.

Referring now to the drawings, and first to Figs. 1 and 2, A is hollow column on the frame (not shown) of the mill, and 1 is the platen which is mounted to rotate idly in a bearing 11 at the upper end of the column A. B is the blank or block on the platen 1, and 5 and 6 are work-supporting pins for holding the blank on the platen. The pins are disposed with their axes in the axis about which the platen rotates, and at opposite sides of the platen. Any suitable means (not shown) may be used for applying the pins to the blank B.

8 are a pair of uprights on the frame of the mill, and 7 is a bridge or bracket which is mounted to slide vertically on the uprights. In its central portion, the bridge is recessed for the platen 1, Fig. 2, and at both ends it has guides 3'. 13 are bearing blocks which are mounted to slide in the guides 3' and 3 are bearings on the blocks 13, each bearing having a shaft 4. Means such as pivots 14 may be pro-

vided for connecting the bearings 3 to their blocks 13 so that the axes of both shafts 4, or one of the shafts, may be inclined at various angles to horizontal. 2, 2 are rolls at the inner ends of the shafts 4. Means, not shown, are provided for rotating the shafts and rolls in opposite directions, as indicated by the arrows E in Fig. 1.

Fig. 1 shows the initial position of the rolls 2, 2 in which they bear on the central portion of the blank B. In operation, the rolls are rotated while at the same time their bearings are withdrawn in the guides 3' in the direction of arrows C. The thickness of the work is regulated by displacing the bridge 7 in the direction of the arrows D. The platen 1 is free to rotate in its bearing 11 and, if the rolls 2 rotate in the direction of arrows E, E in Fig. 1, the platen is rotated anti-clockwise, as indicated by the arrows.

In a mill according to my invention, with driven rolls and an idle platen, as against the old mill referred to in which both the rolls and the platen are driven, much higher rolling pressures can be exerted, and blanks of considerable thickness be rolled into thin disks or other sections, without sticking of the rolls or the platen. The old mill is operative at low pressures only and sticks if the pressure is increased beyond its low limit. The deformation of the work per operation is small in proportion, and therefore the old mill requires many operations, each at low pressure, in order to obtain a given deformation. But even if this is done, there is no safety from sticking and distortions of the work resulting therefrom. Moreover, the frequent annealing deteriorates the material.

Sticking and the distortion of the work resulting therefrom are avoided in the mill according to my invention, and the operation may be performed in a single stage under the high rolling pressure permitted by my improved arrangement. The rolls have no tendency to stick, and sticking of the platen is easily avoided by amply dimensioned bearings for the platen which can be arranged without difficulty.

Not only disks with parallel or tapered faces can be rolled from a blank with my mill, but also cups, troughs, and the like, and some specimens of its work will now be described.

Referring first to Figs. 3 and 4, these show one of the initial stages of the rolling operation, and its final stage, respectively. At the beginning of the operation, the bridge 7 is lowered to bring the rolls 2 to bear on the blank B, the

rolls are rotated and moved apart in the direction of arrows C by their bearings 3, while the bridge 7 is lowered in the direction of the downwardly pointing arrows D. The bridge and the 5 rolls are displaced in parallel directions only and the flat disk B' shown in Fig. 4 is obtained.

I may so design the bearings 3 and/or their guides 3' that the axes of the rolls 2 are at an angle to each other if the bearings or guides are 10 suitably adjusted. Means for adjusting the bearings 3 on their blocks 13 are shown in Fig. 2. The axes may be set at an angle permanently, i. e., the axes may remain at this angle throughout the operation and any suitable 15 means, not shown, may be provided holding the bearings in the position into which they have been moved. With this setting of the axes, the section B² in Fig. 5 is obtained. This section has a flat lower, and a tapered upper face. By 20 maintaining the axes in a straight line for the major part of the operation and gradually varying their inclination at the ends while raising the bridge 7, the section B³ in Fig. 6 is obtained. This is a cup resembling a trough. The spherical cup B⁴ in Fig. 7 is obtained by varying the 25 inclination of the roll axes throughout the operation and gradually raising the bridge 7.

Obviously, a great variety of sections may be obtained by suitably varying the inclination of 30 the axes and raising and lowering the bridge 7.

The hub-and-disk wheel, Fig. 5, is obtained by raising and lowering the bridge 7 without varying the position of the roll axes, so that the section is defined exclusively by straight lines at 35 right angles to each other. Inclined or curved portions of the section are obtained in the manner described by varying the angle of the roll axes.

I claim:

40 1. In a mill for rolling revolution bodies from blanks, a blank-supporting, revolute, idle plat-

en, and a pair of opposed driven blank-working rolls which are adapted to be traversed and re-traversed over said platen towards and away from the center of the latter.

2. In a mill for rolling revolution bodies from blanks, a blank-supporting, revolute, idle platen, means arranged in line with the axis said platen revolves about, for holding the blank on said platen, and a pair of diametrically opposed driven blank-working rolls which are adapted to 10 be traversed and retraversed over said platen.

3. In a mill for rolling revolution bodies from blanks, a blank-supporting, revolute, idle platen, a bridge mounted for displacement in parallel to the axis of said platen, a pair of bearings 15 mounted to slide in said bridge at opposite sides of said platen, a shaft in each bearing, and a driven blank-working roll on each shaft.

4. In a mill for rolling revolution bodies from blanks, a blank-supporting, revolute, idle platen, a bearing on which said platen is mounted to revolve, an abutment for holding said platen against axial displacement in the direction of the rolling pressure, and a pair of opposed driven blank-working rolls which are adapted to be 20 traversed and retraversed over said platen.

5. In a mill for rolling revolution bodies from blanks, a blank-supporting, revolute, idle platen, a bridge mounted for displacement in parallel to the axis of said platen, a pair of blocks 30 mounted to slide on said bridge at opposite sides of said platen, a bearing fulcrumed on each slide, a shaft in each bearing, and a driven blank-working roll on each shaft.

6. In a mill for rolling revolution bodies from 35 blanks, a blank supporting platen mounted to revolve idly, a pair of opposed power driven working rolls, and means to guide the movement of said rolls in a direction substantially radial to the blank supported on said platen.

CARL SCHMIDT.
